UNITED STATES PATENT OFFICE.

NOEL B. CHARTIER, OF RICHLAND, WASHINGTON.

WALL-PAPERING MACHINE.

1,257,315.

Specification of Letters Patent. Patented Feb. 26, 1918.

Application filed April 21, 1916. Serial No. 92,715.

To all whom it may concern:

Be it known that I, NOEL B. CHARTIER, a citizen of the United States, residing at Richland, in the county of Benton and State 5 of Washington, have invented certain new and useful Improvements in Wall-Papering Machines, of which the following is a specification.

This invention relates to wall papering 10 machines, and more particularly to an improved apparatus of the type described, having for its primary object, the coating of wall paper with the usual adhesive and accurately applying the same to a wall.

Another object of the invention is to provide efficient means, whereby the paper may 15 be moved over a plurality of guide rolls into partial engagement with an adhesive or paste, one side of the paper being efficiently 20 coated with paste, and further, upon completion of the coating operation, providing means whereby the paper may be withdrawn from engagement with the tank and a suitable closure moved over the opening 25 created by the withdrawal.

The invention also contemplates the provision of novel means for automatically severing the coated strip of paper from the supply roll, thus, facilitating the application 30 thereof to the wall.

Another important characteristic of the invention resides in the provision of paper trimming mechanism, which will remove the usual blank margin of the paper in order 35 that the same may be properly matched.

Other features of the invention, reside in an improved automatic device which will, when adjusted, cut the paper of sufficient 40 width as to permit the machine to be used for finishing up and also, allow the same to efficiently hang the paper in corners; the provision of means whereby the paper may be held preparatory to its application to the wall, whereupon, the same is automatically 45 released; and means for use in conjunction with the heretofore mentioned automatic severing mechanism, whereby it may be adjusted to cut the paper in various lengths, such as conditions or preference 50 may dictate.

Finally, the invention aims to provide a novel apparatus of the character described, portable in character, easily manipulated, efficient in operation and strong and durable 55 in use; one in which the parts thereof, are closely assembled and combined, thereby

taking up a minimum amount of space, and rendering the device especially applicable for operation in confined places.

All of the foregoing, together with additional advantageous details and arrangement of parts of the preferred embodiment of my invention, will be clear from the specific description hereinafter contained, when read in connection with the accompanying 60 drawings forming a part thereof, wherein the preferred embodiment of my invention is illustrated for the purpose of facilitating a full understanding of the present improvements.

In the drawings:—

Figure 1 is a longitudinal section; Fig. 2 is a horizontal section taken on the line 2—2, looking in the direction of the arrows, of Fig. 1;

Fig. 3 is an elevation showing the tapered supporting guide roll moved from the paste tank and the closure applied to the opening;

Fig. 4 is a fragmental detail partly in section of the cutting knife whereby various 80 widths of paper may be obtained;

Fig. 5 is a detail in perspective, partly in section of the operating member for the automatic strip severing mechanism;

Fig. 6 is a side elevation of the telescopic 85 handle;

Fig. 7 is a detail in section of the flag joint as used in conjunction with the various telescopic sections of the handle;

Fig. 8 is a transverse section through the 90 joint; and

Fig. 9 is a detail in section of the locking means whereby the handle is held in an extended position.

Referring now more specifically to the 95 drawings wherein like reference characters designate like or corresponding parts throughout the several views thereof, I provide a main casing or housing 1 formed of sheet metal or the like and having arranged 100 upon its bottom face, a plurality of brackets 2 and 3 which are adapted to rotatably support rollers 4 and 5. Sockets 6 and 7 are arranged upon the side walls of the casing and are adapted to receive the 105 ends 8 and 9 of a handle attaching bail 10. The horizontal portion of the bail 10 has arranged therein, an opening 11 whereby a washer 12, having its upper face serrated and a handle portion 13 having an enlarged 110 flat head portion provided with a complementally serrated portion 14, may be se-

cured thereto by means of a bolt which is passed through the opening and through suitably alined openings in the serrated washer and enlarged head portion, whereupon the wing nut 15 is turned into engagement with its threaded extremity, in order that the various adjacent elements may be securely clamped in an adjusted position.

The handle portion 13 carries a plurality 10 of telescoping sections, generally numbered 16, the larger of which is provided with an interiorly screw threaded portion 17, whereby a plug 18 having a threaded shank 19 may be received thereinto. To provide 15 means whereby relative rotary movement of the various telescopic sections 16 will be prevented, I provide the adjacent portions thereof, with longitudinally extending grooves, which grooves are adapted to receive laterally distended lugs 21, while in order that the telescopic sections 16 may be held in their extended position, a spring 20 latch 22 is secured to one of the adjacent portions of the telescopic sections as at 23 and is afforded lateral movement by means 25 of an opening 24. Thus, it will be obvious, that when the various sections are extended, the spring catch, due to its elasticity, will spring upwardly and consequently, abut the 30 adjacent sections and accordingly prevent its telescoping. It will be also apparent, that should the operator desire to adjust the handle portion 13 in various positions with relation to the housing 1 of the machine, the wing nut 15 may be turned out 35 of engagement with the bolt, whereupon the interlocking serrated portions may be adjusted.

The transversely arranged pocket 25 is 40 formed upon the upper side of the casing or housing 1 and has formed thereupon, adjacent its rear wall, distended portions 26 and 26' which are so arranged as to constitute an elongated opening or slot. A 45 bracket or holder 27 having arm portions 28 and 28', the outer extremities of which are supplied with suitable openings, is rotatably secured to the casing or housing 1 at a point adjacent one side of the pocket 25, by means of journal bearings, generally indicated at 29. A portion of the bracket member 27 is looped as at 30 intermediate its ends, preferably at the middle thereof, and is received by a keeper 31 secured to the 50 casing as at 32. It will be noted, that the keeper 31 is provided with upon its under face, a dividing element 33. Arcuate springs 34 are also secured to the casing as at 35, at a point directly beneath the dividing element 33. By this arrangement the bracket 27 may be shifted from one position to another, as shown to advantage in dotted lines in Fig. 2, and may, by means of the 55 said arcuate springs 34, be securely held in this adjusted position. A paper roll 36 is

received between the arms 28 and 28' of the bracket 27, the roll having been previously supplied with a core, not shown, which core is supplied with lugs 37, receivable in the openings arranged in the extremities of the said arms 28 and 28'.

Arranged interiorly of the casing 1, is a paste tank 38, the same being secured to the side walls of the casing by means of apertured ears 39, which receive suitable fastening screws or the like 40. Attention is directed to the peculiar construction of the paste tank, the upper portion of which is substantially circular, while the lower portion thereof is reduced, the purpose of which shall be subsequently apparent. A door 41 having a transparent panel, is hingedly secured to the paste tank as at 42, adjacent a complementary opening formed therein and indicated at 43. The door may be supplied 75 with a catch 44, which comprises the usual turning bolt or keeper, whereby the lower marginal edge of the opening 43 may be engaged. An elongated opening 45 is arranged in the reduced portion of the tank 80 85 90 95 100 105 110 115 120 125 130 38, preferably adjacent the lower extremity thereof and has arranged adjacent thereto, interiorly of the reduced portion of the tank 38, a plurality of rolls 46 and 46', which are suitably journaled in the side portions of the tank. The rotary paste applying brush 47 is also journaled interiorly of the tank adjacent to said rolls 46 and 46' and has arranged upon one end thereof, a gear 48 which gear is enmeshed with a gear 49 journaled within the reduced portion of the tank and adjacent the opening 45. A slideable closure plate 50 is provided whereby the opening 45, may be, at times, closed, the said plate being supported and operated through the medium of a link 51 which is pivoted thereto as at 52, while its outer extremity is pivotally secured as at 53, to a lever 54, which lever is, in turn, rotatably supported as at 55 to the side wall of the casing 1. The lever 54 is provided with a handle 56, the handle portion having arranged thereupon, a pivotally connected locking member 57, the lower portion of which is provided with a spring shoe, not shown, which may be engaged with the adjacent side wall of the casing and consequently, due to the friction as created by this engagement, will serve as efficient means for securing the handle portion 56 in an adjusted position. A paper supporting and guiding roll 58 is rotatably supported by a yoke member 59, as at 60 and has secured thereto, adjacent one end thereof, or both ends, if so desired, a gear 61, the gear being adapted to mesh with the gear 49 upon certain occasions. The yoke 59 has arranged thereupon, a vertically extending arm 62, the upper extremity of which is rounded as at 63 and normally engages with the under

side of the enlarged portion of the paste tank 38. Pivotally connected to the vertical arm 62 at a point adjacent its lower extremity, as at 64, is a connecting link 65, the link, 5 in turn, being pivotally connected at its adjacent end, to an oscillating arm 66, the arm being pivotally mounted upon one side wall of the casing as at 67. A link 68 is pivotally connected to the upper extremity of the oscillatory arm 66 and has its remaining extremity similarly connected to the closure plate 50. It will be apparent, that the paper supporting and guiding roll 58, is, through 10 the medium of its pivotally connected supporting means, normally held in a position so that a portion thereof extends through the opening 45 in the reduced portion of the paste tank 38 when the closure plate 50 has been moved from the opening, this being 15 shown to advantage in Fig. 1.

Referring now to the passage of the paper, through the machine, it may be stated, that the strip 36' is unwound from its supply roll 36 and passed through the opening 25 as afforded by the extended portions 26 and 26' of the pocket 25, whereupon, it is threaded over an idler 69, suitably journaled within the side walls, of the casing 1 and then passes downwardly about a second idler 70, 30 also rotatably supported by the side walls of the casing, from where, it passes forwardly about the supporting and guiding roll 58 and is brought backwardly and carried over the roll 5, finally, being brought 35 upwardly and engaged with the roll 4, where it is secured.

To provide for means whereby the paper may be held in engagement with the roll 4 and released at certain times, a plurality of 40 cam surfaces 70 are arranged upon one end portion thereof, and are adapted to engage a trip member 71 upon the lower extremity of a locking finger 72, the upper portion of the locking member having arranged 45 thereupon, a laterally distended arm, not shown. The lower portion of the locking member 72 is reduced as at 73 and has arranged thereabout a coiled spring 74, the spring having one portion thereof, bearing 50 upon a pin 75 arranged in the outer end of the reduced portion, while the remaining portion thereof is secured to one of the bracket members 2. A guide member 76 is secured to the bracket member 2 and has 55 positioned thereupon, a vertically arranged slideable locking pin 77, which pin is normally held or forced inwardly by means of an expansible coil spring arranged thereabout. It is to be understood, that when 60 the trip portion 71 is engaged by one of the cam surfaces 70 the locking member 72 is forced upwardly, consequently, disengaging the laterally extended paper engaging arm and permitting the same to be released. As the locking member 72 is moved 65

forwardly, the pin 77, being forced inwardly, by means of the coil spring will engage with a suitable recess or opening arranged in the adjacent side of the locking member, not shown, thereby serving to hold 70 the same in its unlocked or inoperative position.

A portion of the casing 1 and the bottom thereof is left open and in order to provide means whereby this opening may be normally closed, a cover 78 hingedly secured to the casing as at 79, is provided. An arm 80 is pivotally secured to one side of the closure as at 81 and has arranged thereupon, adjacent its outer extremity, a knife 82, a 80 leaf spring 83 being normally engaged with the under side of the arm 80 at a point adjacent the cutting knife and supported upon the cover by means of an angular bracket 84. A catch 85 is secured to the closure at a point 85 adjacent its outermost extremity, as at 86, and has arranged thereupon, a notched extension 87 which is adapted to engage with a pin 88 supported by one side wall of the casing 1. As the cover is drawn to its closed 90 position, the notched portion 87 will be snapped into engagement with the receiving pin 88 and consequently, held in its closed position until further actuated. A cutting block 89 is arranged adjacent the knife 82 95 and is provided with a groove 90 conforming in depth and shape to the knife. A manually set knife engaging trigger 91 is pivotally secured to the casing at 92, the outer curved extremity thereof, being adapted to engage a portion of the arm 80, adjacent the said knife, while the remaining extremity extends upwardly into engagement with a pin 93 carried in a U-shaped operating arm 94, the arm being slidably received 105 in guide ways 95 provided for by the housing 1. The operating member may be provided with a series of openings 96 which openings may be interiorly threaded for engagement with the pin 93, thus, permitting 110 the same to be adjusted to any one thereof, at the option of the operator. An extended finger 97 is secured to the horizontal portion of the U-shaped operating member by means of a bolt 98. In order that the outward 115 movement of the arm 80 may be limited, a stop 99 is positioned upon one of the side walls of the cover 78 in the path thereof.

In wall papering, it is also necessary that the paper be cut into varying widths in 120 order that the same may be applied to corners or other places where the ordinary width of paper would be too great. In order to provide for means whereby the paper as rolled from its supply may be cut so that 125 various widths thereof may be obtained, I provide a roller 100, journaled in suitable bearings in the side walls of the casing 1 and provided with a plurality of circumferentially extending grooves 101. The trans- 130

versely arranged shaft 102 having the ends thereof disposed within suitable depressed guide ways 103 is provided. Connected with the shaft is a pivotally supported arm 104, 5 which is guided throughout its travel by means of a quadrant 105, having arranged thereupon, a series of seats or the like 106, which seats are adapted to be engaged by a reciprocable locking pawl 107, carried upon 10 the arm or lever 104 and actuated by means of a handle member 108. It will be evident that by this arrangement, the transverse shaft 102 may be adjusted toward and from the strip of wall paper 36', thus, permitting 15 the cutting disk 109 as carried thereupon to be suitably engaged with the paper. Normally, the cutting disk 109 is arranged upon the shaft at a position adjacent its outermost extremity, shown to advantage in Fig. 4, 20 whereupon, the same will serve to remove the blank marginal edge 110 from the pattern paper. Should the operator desire to obtain a narrow strip of paper for the purposes as above outlined, the set screw 111 as 25 arranged in the collar 112, which carries the cutting disk 109, is turned out of engagement with the transverse shaft 102 whereupon the said cutting disk may be adjusted laterally into the desired position, it of 30 course being understood that the cutting edge thereof must aline with one of the various circumferential grooves 101. Accordingly, as the paper is drawn under the cutting disks, the desired amount will be 35 severed from one side thereof.

In filling the paste tank, the machine as a 40 whole is inverted, the door 41 is swung into an open position whereupon, the paste may be forced thereinto, the casing being provided with an opening 113 for this purpose. When the filling operation has been completed, the door may be then closed and locked in its position and the machine again 45 reversed whereupon the paste will be directed into the reduced portion of the tank. It will be also apparent, that by the arrangement of the transparent panel in the door 41, the operator may readily ascertain the amount of paste as contained by the tank.

50 In reviewing the operation of the machine, and assuming that the paste tank 38 has been filled and that the paper roll 36 has been inserted and threaded about the various idlers and guide rolls until the rear extremity thereof is received within the pocket member 72, the machine is moved downwardly, causing the wall paper to be unwound from its supply roll and passed about the supporting and guide roll 58, during which movement, it 55 will be engaged by the paste applying roll or brush 47. Upon further movement thereof, it will pass the lower guide roll 46 which will serve as efficient means for spreading the paste evenly over the surface thereof, 60 from whence it will be carried downwardly

over the cutting block 89 and into engagement with the rolls 4 and 5. As the machine is moved downwardly, the laterally extended finger 97 is engaged with the base board of the wall, consequently, forcing the 70 U-shaped operating lever 94 upwardly, causing the pin 93 to be engaged with the outer extremity of the trigger 91, thus, disengaging the same from the cutting knife 82. This member is, due to its resilient mounting, then forced forwardly into engagement with the groove 90 as contained in the cutting block 89, whereby, the paper will be severed. Should the operator desire to discontinue his work, the handle 56 is forced 75 upwardly, the catch or locking member 57 having been previously disengaged from the side wall of the casing, which movement will, by means of the various pivotally connected links, force the closure plates 50 80 downwardly, and, at the same time, force the supporting and guide roll 58 to be withdrawn from the opening 45 of the paste tank. Upon continued movement of the closure plate, the opening 45 will, accordingly, be closed and waste of the paste or adhesive will be prevented. Upon subsequent usage of the machine, the handle 56 is moved downwardly which will permit the closure plate 50 to be withdrawn from the 85 opening 45 and also allow the supporting and guide roll 58 to be moved into engagement with the said opening. It will be evident, that as the roll 58 is engaged with the opening 45, the gear 61 as carried thereby, 90 will be engaged with the gear 49, which is journaled in the reduced portion of the paste tank 38 and in mesh with the gear 48 upon the paste applying brush. Due to the manner in which gear 61 is engaged with the 95 said gear 49, a rotary motion will be imparted thereto, and accordingly, transmitted to the gear 48, causing the rotation of the paste applying brush 47. By this operation, the flow of paste onto the exposed 100 surface of the wall paper will be discarded and also will be evenly applied thereto.

105 Wall paper as usually marketed, is provided with a blank margin, as designated at 110 upon the drawings, and, in order to remove this blank margin, the bracket 27 is shifted laterally so that the pattern edge of the paper will be alined with the cutting disk 109. Due to the slideable mounting of the bracket, the roll 36 may be adjusted to 115 either side of the machine, this depending upon the location of the blank marginal edge. When corners have been reached, or whenever the operator is desirous of using narrow strips of paper, the cutting disk 109 120 is accordingly adjusted laterally upon its transverse supporting bar 102, until the desired width has been reached, whereupon the same is secured in its adjusted position 125 by means of the screw 111, this, serving as 130

means whereby the superfluous portion of the paper may be severed therefrom.

Attention is also directed to the fact, that the strip severing mechanism may be readily 5 adjusted so as to provide for strips of varying length, by the mere replacement of the pin 93. For instance, should the operating member 94 be extended, and the pin 93 inserted within the transverse opening 96, the 10 cutting mechanism will be accordingly actuated upon engagement of the extended finger 97 with the base board. It is also obvious, that the said extended finger 97 may be readily removed from the device and 15 that the cutting mechanism may be actuated by the engagement of the operating member 94 with the floor of the room.

Should access to the various parts of the interiorly arranged apparatus be desired, 20 the hingedly mounted cover 78 may be readily swung downwardly by releasing the catch 85.

While I have herein disclosed the specific embodiment of the invention, it will 25 be apparent to persons skilled in the art, that the invention is capable of embodiment in other forms and devices differing in detail and arrangement from that shown as may be in keeping with the hereto appended claims.

Having thus described the invention, what I claim is:—

1. A wall papering machine, including a housing, means for supporting a roll of paper upon said housing, laterally adjustable means for removing the marginal portion of said paper, paste applying means carried by said housing, means for applying the paper to the wall as it leaves said paste 35 applying means, and means for severing said paper from the roll, and adjustable means for operating said last mentioned severing means.

2. A wall papering machine, including a housing, means for supporting a roll of paper upon said housing, vertical laterally adjustable means for removing the marginal portions of said paper, paste applying means carried by said housing, means for 45 applying the paper to the wall as it leaves said paste tank, means for severing said paper from the roll, and adjustable means slidably carried by said housing for operating said last mentioned severing means.

3. A wall papering machine, including a housing, laterally adjustable means for supporting a roll of paper upon said housing, adjustable means for removing the marginal portion of said paper, paste applying 55 means carried by said housing, means for applying the paper to the wall as it leaves said paste applying means, and automatic means for severing said paper from the roll.

4. A wall papering machine, including a

housing, laterally adjustable means for supporting a roll of paper upon said housing, vertical laterally adjustable cutting means for removing the marginal portion of said paper, paste applying means carried by said 70 housing, means for applying the paper to the wall as it leaves said paste applying means, and automatic means for cutting the paper from the roll.

5. A wall papering machine, including a 75 housing, laterally adjustable means for supporting a roll of paper upon said housing, vertically and laterally adjustable cutting means for removing a marginal portion of said paper, a paste tank within said housing, means for guiding the paper from said roll through said paste tank, means for applying paste to the paper passing through said tank, means for applying the paper to the wall as it leaves said paste tank, means 80 for cutting and severing said paper from the roll, and adjustable means for operating said last mentioned severing means.

6. A wall papering machine, comprising a housing, adjustable means for supporting 90 a roll of paper upon said housing, adjustable means for removing a marginal portion of said paper, a paste tank arranged within said housing, means for guiding the paper from the roll through said paste tank, 95 means for applying paste to the paper passing through said tank, means for removing the paper from engagement with the paste tank, means for preventing the waste of paste from said paste tank, means for applying the paper to the wall as it leaves said paste tank, and automatic means for severing said paper from the roll.

7. A wall papering machine, including a housing, laterally adjustable means for supporting a roll of paper upon said housing, means for retaining said first mentioned means in a set position, a paste tank within said housing, means for guiding the paper in said roll through said paste tank, a rotary brush for applying paste to the paper passing through said tank, means for applying the paper to the wall as it leaves said paste tank, and means for automatically severing the paper from the roll.

8. A wall papering machine, including a housing, a laterally movable bracket positioned upon said housing for supporting a roll of paper, a paste tank within said housing, a keeper carried by said housing for 110 retaining said bracket in an adjusted set position, means for guiding the paper from said roll through said paste tank, a rotary brush for applying the paste to the paper passing through said tank, and means for applying the paper to the wall as it leaves said paste tank.

9. A wall papering machine, including a housing, a laterally movable bracket positioned upon said housing, said bracket hav- 130

ing a loop, a keeper carried by said housing, said keeper having a plurality of seats, springs carried by said housing in alignment with said seats, whereby said loop may 5 be releasably retained in one of said seats, a paste tank within said housing, means for guiding the paper from said roll through said paste tank, a brush for applying paste to the paper passing through said tank, and 10 means for applying the paper to the wall as it leaves said paste tank.

10. A wall papering machine comprising a housing, means for supporting a roll of paper upon a housing, a paste tank arranged within said housing, means for guiding the paper from the roll through said paste tank, means for applying paste to the paper passing said tank, means for removing the paper from engagement with the 20 paste tank, means for preventing the waste of paste from said tank, and means for applying the paper to a wall.

11. A wall papering machine comprising a housing, means for supporting a roll of paper upon said housing, a paste tank arranged within said housing, said paste tank having an opening, means for guiding the paper from the roll through said tank, and including a guiding roller, a plate movably 25 mounted upon said paste tank, means for simultaneously moving said plate over said opening and said guide roller away there-

from, and means for applying paper to a wall as it leaves said paste tank.

12. A wall papering machine comprising 35 a housing, means for supporting a roll of paper upon said housing, a paste tank carried by said housing, said tank having an opening, a guiding means including a guide roller interposed within said opening, means 40 for applying paste to the paper passing through said tank, a plate movably mounted upon said tank, links connecting said roller to said plate, whereby said roller may be retracted and said plate moved over said 45 opening and means of applying the paper to a wall as it leaves said paste tank.

13. A wall papering machine, including a housing, laterally adjustable means for supporting a roll of paper upon said housing, 50 a paste tank within said housing, means for guiding the paper from said roll through said paste tank, a rotary brush for applying the paste to the paper passing through said tank, means for applying the paper to the wall as it leaves said paste tank, and means for automatically severing the paper from the roll. 55

In testimony whereof I affix my signature in presence of two witnesses.

NOEL B. CHARTIER.
